Size of tool inlet.

Volume of air.

INVENTOR

Ira H. Spencer
BY
Arthur B. Jenkins,
ATTORNEY

UNITED STATES PATENT OFFICE.

IRA H. SPENCER, OF WEST HARTFORD, CONNECTICUT, ASSIGNOR TO THE SPENCER TURBINE CLEANER COMPANY, OF HARTFORD, CONNECTICUT, A CORPORATION OF CONNECTICUT.

TESTING APPARATUS.

1,198,396.

Specification of Letters Patent. Patented Sept. 12, 1916.

Application filed January 17, 1912. Serial No. 671,632.

To all whom it may concern:

Be it known that I, IRA H. SPENCER, a citizen of the United States, and a resident of West Hartford, in the county of Hartford and State of Connecticut, have invented a new and Improved Testing Apparatus, of which the following is a specification.

My invention relates to an apparatus of the kind above named and an object of my invention, among others is to provide such an apparatus especially designed to show the degree of vacuum that will exist in a cleaning apparatus under varying known conditions as to the size of inlet of the tools 15 in ordinary use and especially to denote this vacuum at the end of the hose to which such tools are attached.

A further object of the invention is to show the volume of air that will pass 20 through any of such tools with a given degree of vacuum; and a further object of the invention is to provide a simple and effective device for readily determining the conditions above set out.

One form of device embodying my invention and in the construction and use of which the objects above set out, as well as others, may be attained is illustrated in the accompanying drawings, in which—

Figure 1 is a view in side elevation of a tester embodying my invention. Fig. 2 is a view in central longitudinal section through the same. Fig. 3 is a detail view showing a development of the table used in connection with the index.

In the accompanying drawings the numeral 5 denotes the body of the tester which is of tubular form, preferably cylindrical, with a cap 6 secured to and closing one end, 40 this cap having a neck 7 with a slot 8, the end of the neck being closed as clearly shown in Fig. 2 of the drawing.

A piston 9 is fitted to move within the body 5, this piston being of any ordinary construction to prevent the flow of air around it. A hollow extension 10 from the piston is located within the neck 7 and contains a spring 11 secured at one end to the bottom of the well within the extension and 50 the opposite end of the spring being secured to a threaded stud 12 engaging a screw threaded opening in an adjusting nut 13 seated on the end of the neck 7. The end of the extension 10 is formed into a lip 55 constituting an indicator 14, which, acting

in connection with the table 15 on the neck, serves to determine the degree of the vacuum.

The body 5 is preferably of a size to fit closely within the end of a hose or tube to which cleaning tools are commonly attached, and it has an inlet opening or openings 16, two of such openings being shown herein. A gate 17, preferably in the form of a sleeve and having a series of ports 18, is mounted on the body to control each of the openings or series of openings 16. The ports in each gate are of different sizes each from another, the area of each being made to correspond to the area of an opening in a cleaning tool, the area of each port being such that the same amount of air will be admitted therethrough as through the corresponding tool in operation under ordinary conditions of use, so that by causing a certain opening in a gate to register with the opening 16 in the body the same amount of air will pass into the hose as would be supplied thereto by a tool having an opening corresponding to the size of the port in the gate, and the vacuum in the hose will cause the piston to be displaced and thus indicate the amount of vacuum which would be present in the hose with a tool of any given size.

By reference to corresponding areas as to the openings in the gate and in cleaning tools, is not necessarily meant that the openings in the gate are of the same area as those in the tools, but that they are such as to admit the same amount of air as will be admitted to the tools under ordinary conditions of use. The tools when placed upon a surface will take in a certain amount of air less than would be taken in if the tool were raised a considerable distance from such surface and as the tool is rocked more air will be taken in in some positions than in others. The holes in the gate are of a size to take in the average amount of air that will be supplied to the tool during the ordinary conditions of use and they, therefore, correspond to the effective inlet areas of the different tools usable with said tube.

The table 15 is so arranged that in connection with the characters indicating a given amount of vacuum there will also be indicated the amount of air that with that vacuum will pass through that opening in a given time, so that the indicator not only

indicates the amount of vacuum present but also the amount of air which is being passed.

My invention provides a simple and inexpensive tool which will accurately determine the amount of vacuum in a hose with the use of tools of varying size, and while I have shown the preferred form of construction of such a tool, this construction may be departed from to a greater or lesser extent 10 and yet embody the invention.

I claim—

1. A pneumatic testing device including a body formed for removable attachment to a tube and having an air inlet opening, a piston located within the body to be moved by the air pressure, means for varying the area of said opening to areas of definite dimensions to correspond to the effective inlet areas of different tools usable with said 15 tube, an indicator mounted for operation by the movement of the piston, and means for mechanically moving the piston in one direction.

2. A pneumatic testing device constituting 25 a complete article of manufacture and including a tubular body formed for removable attachment to a tube and open at one end for insertion in a tube and having an air inlet opening, means for varying the area 30 of said opening to areas of definite dimensions corresponding to the effective inlet areas of different tools usable with said tube, a piston located within the body to be moved by air pressure, means for mechanically 35 forcing the piston in one direction, and means for determining the amount of movement of the piston to denote the density of air passing through the inlet opening.

3. A pneumatic testing device constituting 40 a complete article of manufacture and including a body formed for removable attachment to a tube and having an opening at one end, an air inlet opening into said body, a ring mounted upon the outer surface 45 of the body and constructed to vary the area of said inlet opening to areas of definite dimensions corresponding to the effective inlet areas of different tools usable with said tube, a piston mounted in the body 50 to be moved by air pressure therein, means for mechanically moving the piston in one direction, and means for determining the amount of movement of the piston to denote the density of air passing through the inlet 55 opening.

4. A testing device including a body formed for removable attachment to a tube and having an opening at one end and an inlet opening thereto, a ring rotatably 60 mounted upon the outer surface of the body and having a number of openings of different areas each of an area corresponding to the effective inlet area of a tool usable with said tube, said openings being positioned to 65 register one at a time with said inlet opening

to said body, a piston located within the body and controllable by the air pressure therein, means for mechanically forcing the piston in one direction, and means for determining the amount of movement of the piston in the opposite direction.

5. A pneumatic testing device constituting a complete article of manufacture and including a body having an opening at one end and an inlet opening, means for varying 75 the size of said inlet opening to predetermined and definite dimensions, a cap removably secured to the other end of the body, a neck extending from said cap, a piston located within the body and having a tubular extension within said neck, a spring located within said extension and secured to a stationary part of the device and to the piston to force the piston in one direction, said piston being movable in the opposite direction by air pressure, and means for determining the amount of movement of the piston.

6. A testing device constituting a complete article of manufacture and including a 80 tubular body formed for removable attachment to a tube and open at one end and having an inlet opening located in the side wall of said body, a gate movably mounted on the body and having a number of openings 95 of different sizes and each of an area corresponding with the effective area of a tool usable with said tube, said openings being positioned to fully register one at a time with said inlet opening to vary its size to 100 a definite and predetermined dimensions, a piston located within the body to be moved by air pressure in one direction, means for moving it in the opposite direction, and means connected with the piston and arranged to determine the amount of movement thereof.

7. A testing device constituting a complete article of manufacture and including a tubular body having an open end adapted to 110 be removably inserted in a hose or like part, said body having an opening through its wall, a piston located within the body to be moved by air pressure in one direction, means for moving it in the opposite direction, a cap secured to close the other end of the body and having a projecting neck with a slot in its side wall, a projection from said piston located opposite said slot to indicate the position of the piston, and a gate rotatably mounted on the body and having openings of predetermined and various sizes located to register one at a time with said inlet opening.

8. A pneumatic testing device including a 125 body formed for removable attachment to a tube and with an opening to communicate with the opening in said tube and an effective inlet opening, means including the bounding walls of openings of different di- 130

5 dimensions adapted, in coöperation with the inlet opening to said body, to vary the area of said inlet opening to areas of definite dimensions to correspond with the effective inlet areas of different tools usable with said tube, and an indicator connected with the device to denote the pressure contained therein.

9. A pneumatic testing device including
10 a body formed for removable attachment to a tube and having an air inlet opening therein, a gate movably mounted upon said body and having a number of openings of different dimensions positioned to register with
15 the opening in said body to vary the area of said opening to areas of definite dimensions to correspond to the effective inlet areas of different tools usable with said tube, and an indicator connected with the

device to denote the condition of the pressure therein.

10. A pneumatic testing device including a body formed for removable attachment to a tube and with an opening to communicate with the opening in said tube, said body having a chamber therein, a gate movably mounted on said body, one of said parts (body or gate) having an inlet opening and the other of said parts having a number of openings of different dimensions positioned to register with said inlet openings to vary the effective area of said inlet opening, and an indicator connected with the device to denote the condition of the pressure therein.
